(57) **CLAIM**

The ornamental design for an omnidirectional antenna as shown and described.

DESCRIPTION

FIG. 1 is a perspective view of an omnidirectional antenna showing our new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of the omnidirectional antenna shown within the area designated as 9 in FIG. 1;

FIG. 10 is an enlarged view of the omnidirectional antenna shown within the area designated as 10 in FIG. 1;

FIG. 11 is an enlarged view of the omnidirectional antenna shown within the area designated as 11 in FIG. 1;

FIG. 12 is an enlarged view of the omnidirectional antenna shown within the area designated as 12 in FIG. 2;

FIG. 13 is an enlarged view of the omnidirectional antenna shown within the area designated as 13 in FIG. 5;

FIG. 14 is a perspective view of the omnidirectional antenna in an open state; and,

FIG. 15 is a perspective view shown in a further extended open state.

The broken lines in the drawings are for the purpose of illustrating portions of the omnidirectional antenna that form no part of the claimed design. The dot-dashed broken lines in FIGS. 1-2, 5, and 9-13 show the boundary of the enlarged view and form no part of the claimed design.
